VALVE GRINDER

Filed August 21, 1924

UNITED STATES PATENT OFFICE.

EARL F. MONOHON, OF SANTA MONICA, CALIFORNIA.

VALVE GRINDER.

Application filed August 21, 1924. Serial No. 733,372.

This invention relates in general to a device particularly adapted to grind the poppet valves of internal combustion motors, and the main object is to provide a valve 5 grinding device capable of being manually operated for oscillating the valve in opposite directions, at regularly timed intervals through the medium of a reciprocable operating member.

More particularly the object is to provide 10 a device embodying an oscillatable stem, or spindle, upon which is mounted a manually reciprocable operating member arranged to rotate the stem in a given direction when the 15 operating member is moved in one direction, and to rotate said stem in an opposite direction when the operating member is moved in the other direction.

A further object is to provide means 20 whereby after each return stroke of the operating member the succeeding stroke thereof will effect the reversal of the mechanism for continuing the rotation of the stem in the same direction as on the preceding stroke.

A further object is to provide a fly wheel 25 on the stem of the device whereby the momentum set up in a given stroke of the operating member may be utilized for effecting the reversal of the mechanism for the purpose stated.

A still further object is to provide means 30 on the stem and adapted for resilient engagement with the operating member for cushioning the operation of the operating member on the down-stroke and for urging the same upwardly at the beginning of the up-stroke, thus insuring the reversal of the device at the completion of each cycle of operation.

Other objects may appear as the description progresses. I have shown one practical embodiment of my invention in the accompanying drawing, in which:

Fig. 1 is an external view of the assembled device;

Fig. 2 is a longitudinal section of the same;

Fig. 3 is a transverse section of the same on line 3—3 of Fig. 2;

Figs. 4 and 5 are enlarged diagrammatic views showing the peripheral grooves on the stem of the device with the dogs engaging the grooves at different positions;

Fig. 6 is a perspective view of one of the operating dogs;

Fig. 7 is a face view of a tool such as is adapted to be attached to the stem of the device for connection with a valve to be ground by means of my device;

Figs. 8 and 9, are top plan views of different types of poppet valve heads to which the tool shown in Fig. 7 may be attached for oscillating the valves in a grinding operation.

My device includes as primary elements 65 thereof a substantially elongated stem S having a handle H on the upper end thereof, a fly wheel W on the lower end thereof, a hand grip G slidably and rotatably held on the intermediate portion thereof, and a suitable tool T detachably held on the lower end adjacent the fly wheel W for engagement with a valve V, as shown in Fig. 2.

Stem S has two pairs of reversely formed helical grooves g, g, and g', g' on the periphery thereof which are slightly wider at their tops than at their bottoms. Said pairs of grooves intersect at point 17, 17, etc., and are generally formed in a manner somewhat similar to the well known types of 75 screw drivers in which such grooves are employed. The lead of the two pairs of grooves is the same and the number of turns around the stem S may be changed from the showing of the drawings, as may be found necessary 80 in the operation of a valve grinder. Said grooves are open at the upper end of stem S and at the lower end thereof one of the grooves g and one of the grooves g' intersect and are continued in a longitudinal 85 groove portion 18 on one side of the stem S while the other groove g and the other groove g' intersect and continue in a straight longitudinal groove 18 on the diametrically opposite side of stem S. 95

Hand grip G may be formed of wood or composition material as desired and provided with a metallic sleeve G' extending throughout the entire length thereof and held in grip G by means of one or more set 100 screws 30. A pair of dogs D, D, are carried in the sleeve G' for engagement with the grooves g, g, and g', g', for the purpose of rotating the stem S when the grip G is moved longitudinally of the stem S. 105 Said dogs have stems 19 which are loosely held in apertures 20 in the sleeve G' and right angularly formed portions 21 and 21' which correspond in cross section to the form of the grooves g, g, and g', g'. 110

The device is adapted to be held in a vertical position when in use so that the portions 21 of the dogs D, will point downwardly while the portions 21' thereof will be directed upwardly. The portions 21' of said dogs are preferably pointed at the ends thereof, as shown in Fig. 6, and the length of the dogs from the lower ends of portions 21 to the upper ends of portions 21' is slightly greater than the openings 17 at the intersections of the grooves g, g, and g', g'. Thus during the movement of the grip G on stem S the dogs will span the intersections 17 and guide the grip G in its movement.

At the lowermost points of intersections of grooves g and g' as at 18' the grooves are widened so as to permit the turning of the portions 21' of said dogs to permit the reversal of the device as hereinafter described.

Stem S has a reduced lower end portion S'' with a bore formed therein for receiving the stem 4 of a suitable tool T and the fly wheel W is carried on the portion S'' and may be held by means of a set screw 2 which is threaded into the hub 25 of said wheel and also has a reduced inner portion 2' extending through the portion S'' and into the stem 4 of the tool T. Thus the same set screw 2 which holds the fly wheel on the stem S may be employed for holding the tool stem in position on the device.

Tool T may be of any suitable form but usually it partakes of one of the forms shown in Figs. 1, 2 and 7 and constitutes a flat member with a blade 16 as shown in Figs. 1 and 2, or a pair of prongs 12, 12 as shown in Fig. 7. The upper portion 12' of the tool may be held in a slot in the end of the stem 4 by means of a pin t so that it may be quickly removed and attached to the stem. The poppet valves V which are adapted to be ground in their seats by means of my device are of the form shown in Figs. 2, 8 and 9 and are adapted to engage the beveled seats 10 in a cylinder C. Said valves may have a pair of holes 11, 11 on the heads thereof for receiving the prongs 12, 12 of the tool T, or they may have a single diametrically formed groove 13 for receiving the flat blade 16 of said tool.

The inner end of hub 25 of the fly wheel W is turned to slidably receive a metallic sleeve 26, and is also counterbored at 24 to receive the lower end of a spring A which encompasses the portion S'' of the stem S. The upper end of spring A bears against a leather washer 27 which abuts the end web 26' of sleeve 26 and said spring serves to urge the sleeve 26 upwardly. Grip G has a counterbore in the lower end thereof which carries a leather washer 28' and into which the upper end of sleeve 26 is adapted to project when the grip reaches its lowermost limit of movement. The two washers 27 and

28' serve to cushion the impact between the metallic portions of the device at the lowermost limit of each stroke and the engagement of the grip G with the sleeve 26 compresses the spring A and cushions the grip in its movement.

Handle H at the upper end of the device carries a bushing b which loosely fits the reduced upper end S' of stem S and forms a bearing for the handle on said stem. Handle H is rotatably held on stem S, by means of a screw 1 which extends through a retaining washer b' on the upper end of the handle and is secured to the end portion S' of the stem S, as shown in Fig. 2.

Thus, when the device is positioned for use with the stem S in a substantially vertical position, the tool T, may be loosely connected with the valve V in the manner hereinbefore described, and sufficient pressure exerted on the handle H at the top of the stem S to hold the device in operative connection with said valve.

Now, in operation, the grip G is moved upwardly and downwardly on stem S by grasping the same with the hands in such a manner that the rotation of said grip may be prevented, and the reciprocal movement of said grip will effect the rotation of the stem S, due to the connection therebetween by means of the pair of dogs D, D, as hereinbefore described.

Assuming that the grip is positioned at its lowermost limit of movement at the beginning of a valve grinding operation, the dogs D, D, will engage the straight portions 18, 18 of one pair of the grooves, either g, g, or g', g', as the case may be. On the following up-stroke of the grip G the dogs D, D, will slide upwardly in the selected pair of grooves and on the succeeding down-stroke thereof said dogs will move downwardly in the same grooves. Thus on the up-stroke of the grip the stem S will be rotated in one direction and on the following down-stroke thereof said grip will rotate said stem in a reverse direction.

When the grip G engages the sleeve 26, however, the spring A is compressed and tends to urge the grip upwardly, and the momentum set up by the rotation of the stem and fly wheel W tends to swing the dogs D, D, in a direction corresponding to the previous direction of movement of the stem S. Before the effect of the momentum is nullified, the action of spring A will effect a sufficient upward movement of grip G so as to direct the dogs D, D, into the other set of grooves g, g, or g', g', and the succeeding upward movement will rotate the stem S in the same direction as was effected by the next previous downward movement of the grip. In other words at the completion of each cycle of movement the next

movement of the grip will continue the rotation of the stem S in the same direction it was previously moved.

The purpose of this continuation of movement in a given direction is to provide ample movement in one direction without enlarging the device beyond dimensions which will be convenient to the operator. In order to provide a practicable device the grooves 5 *g*, *g*, and *g'*, *g'*, should be formed with a long lead around the stem S, at least one and one half turns, which will provide means for rotating the stem S for a corresponding number of revolutions on each half stroke 10 of the grip G. Thus at each stroke of the device the stem is rotated one and one half revolutions, by means of the reversing mechanism shown and described, the valve V would be rotated three complete revolutions 15 before the reversal thereof.

The device is best operated by gripping the member G with one hand loosely and by manually moving the same upwardly and downwardly on the stem S with an easy 20 movement and without effort so that the spring A at the bottom of the stroke may become effective for reversing the dogs D, D, due to the momentum of the wheel W.

As in other devices the grinding compound 25 is placed on the beveled surface of the valve V and on the seat 10 and the continued operation of the tool T serves to thoroughly grind the valve in its seat. Valve V may be urged upwardly by slight spring tension 30 so that the weight of the grinder will be sufficient to seat the valve in the grinding operation.

The junction points 18', 18' of the grooves 35 *g*, and *g'* and the portions 18 are of substantially greater area than the grooves proper so as to provide ample space in which to effect the reversal of the dogs D, D, when the same are at their lowermost limits of movement. It will be understood in this 40 connection that said dogs may only be reversed at their lowermost limits of movement, and that the reversal of direction of rotation of stem S is accomplished by the return of the dogs in the same grooves which 45 they traversed on the upward stroke of grip G. The change from one pair of grooves to the other does not reverse the direction of rotation but on the other hand continues the rotation in the same direction that the stem 50 was rotated on the next previous down stroke of grip G.

I am well aware that other devices have heretofore been made and used embodying 55 a pair, or pairs of reversely formed grooves on a stem of the character shown, but I am not aware that the particular arrangement for reversing the dogs in the grooves and for joining the grooves as shown, has ever been used or known.

60 I conceive it to be possible to modify my

invention within the scope of the appended claims without departing from the spirit thereof.

What I claim is:

1. A tool of the character described comprising a shaft having a pair of reversely formed spiral grooves on the periphery thereof, said grooves terminating near one end of said shaft at diametrically opposite points, and provided with longitudinal extensions, the sides of the grooves connecting the spiral and longitudinal portions thereof being formed so as to gradually widen the grooves in the direction of the spiral portions, and an operating member slidable on 70 said shaft and having dogs pivotally held therein with elongated portions engaging said grooves, as described.

2. A tool of the character described comprising a shaft having a pair of reversely formed spiral grooves on the periphery thereof, said grooves terminating near one end of said shaft at diametrically opposite points, and provided with longitudinal extensions, the sides of the grooves connecting 85 the spiral and longitudinal portions thereof being formed so as to gradually widen the grooves in the direction of the spiral portions, an operating member slidable on said shaft and having dogs pivotally held therein 90 with elongated portions engaging said grooves, and means supported on said shaft and cooperating with said operating member whereby at the end of a stroke of said operating member said dogs will be moved pivotally as they enter the longitudinal portions 95 of said grooves for changing the dogs from one of said grooves into the other for a reverse operation.

3. A tool of the character described comprising a shaft having a pair of reversely formed spiral grooves on the periphery thereof, said grooves terminating near one end of said shaft at diametrically opposite points, and provided with longitudinal extensions, the sides of the grooves connecting the spiral and longitudinal portions thereof being formed so as to gradually widen the 100 grooves in the direction of the spiral portions, an operating member slidable on said shaft and having dogs pivotally held therein 105 with elongated portions engaging said grooves, a balance wheel fixed to said shaft for causing said dogs at the end of a stroke of said operating member to disengage one 110 of the sides of the associated grooves, and to engage the other sides of said grooves for continuing the rotation of the shaft, in the same direction on the ensuing up-stroke of 115 said handle.

4. A tool of the character described comprising a shaft having a pair of reversely formed spiral grooves on the periphery thereof, said grooves terminating near one 120 end of said shaft at diametrically opposite 125

points, and provided with longitudinal extensions, the sides of the grooves connecting the spiral and longitudinal portions thereof being formed so as to gradually widen the grooves in the direction of the spiral portions, an operating member slideable on said shaft and having dogs pivotally held therein with elongated portions engaging said grooves, a balance wheel fixed to said shaft

10 for causing said dogs at the end of a stroke

of said operating member to disengage one of the sides of the associated grooves, and to engage the other sides of said grooves for continuing the rotation of the shaft in the same direction on the ensuing up-stroke of 15 said handle, and means interposed between said balance wheel and said operating member for cushioning the movement of said operating member.

EARL F. MONOHON.
